UNITED STATES PATENT OFFICE.

GEORGE W. WOODS, OF NEW YORK, N. Y.

COMBINED BURNER AND HEATER.

Application filed November 25, 1921. Serial No. 517,724.

To all whom it may concern:

Be it known that I, GEORGE W. Woods, a citizen of the United States, residing at New York, in the county of New York and State of New York, have invented certain new and useful Improvements in Combined Burners and Heaters, of which the following is a specification.

This invention relates to combined burners and heaters, and has for one of its objects to provide a device wherein hydro-carbon fuel in its various forms is adapted to be employed and in which the liquid fuel is transformed into a highly combustible gas with decreased expense and with increased intensity.

Another object of the invention is to provide a device of this character which is compact, easily installed, and wherein the liquid hydro-carbon and water are commingled in the proper proportions and simultaneously vaporized.

Another object of the invention is to provide a device of this character in which the hydro-carbon and water elements are vaporized by the action of a preliminary heater or burner and thus preheated before passing to the main burner.

Another object of the invention is to provide a device of this character wherein a minor portion of the gas generated is utilized to generate an increased supply of gas leaving the major portion of the gas available for heating.

Another object of the invention is to provide a device of this character so arranged that the heated air is uniformly diffused and distributed uniformly in all directions.

Another object of the invention is to provide a device of this character including a gas generator, a preliminary burner and a main burner with means whereby a minor quantity of the gas is utilized to supply the preliminary burner and to heat the air and cause it to circulate over the main burner, thus leaving the major portion of the gas available for use in the main burner.

Another object of the invention is to provide a device of this character which is self contained, furnishes its own heated air and thereby materially increases the efficiency of the combustion.

Another object of the invention is to provide a device of this character wherein the heat radiated from the generating chamber

and rising from a preliminary burner is utilized to impart preliminary heat to the air passing to a main burner.

With these and other objects in view, the invention consists in certain novel features of construction as hereinafter shown and described and then specifically pointed out in the claims, and in the drawings illustrative of the preferred embodiment of the invention;

Figure 1 is a side elevation.

Fig. 2 is a vertical sectional elevation.

Fig. 3 is a plan view with the feed pipes for fuel and water in transverse section.

Fig. 4 is a transverse section on the line 4—4 of Fig. 2.

Fig. 5 is a transverse section on the line 5—5 of Fig. 2.

Fig. 6 is a transverse section on the line 6—6 of Fig. 2.

Fig. 7 is a detail perspective view illustrating the construction of the air conductor flues.

Fig. 8 is an enlarged sectional detail illustrating the construction of the strainer caps 80 for the air inlet tubes.

Fig. 9 is an enlarged sectional detail of the check valve between the vaporizing chamber and the main burner.

The improved apparatus comprises a base 85 member 10 upon which a lower shell member 11 is mounted and provided with a plurality of air apertures 12.

The lower shell member 11 is provided with one or more side openings covered by 90 swinging doors 13 of suitable construction to provide access to the interior of the lower shell.

The lower shell 11 is also provided with an encompassing ring 14 to form a support 95 for an upper shell comprising a cylindrical side wall 15, upper end 16 and lower end 17, the three members 15, 16 and 17 being united gas tight, and constituting a generating chamber.

The end members 16 and 17 of the upper shell are each formed with a relatively large central opening surrounded by attaching flanges to support a tubular member 18.

Connected at 19 to the lower end member 17 is a cylindrical support 20 depending below the ends 17 and provided with an internally threaded opening to support the lower threaded end of a conductor tube 21 110

which extends through the tubular member 18 and above the upper end 16 of the generator and is flared outwardly as shown at 22.

5 Leading inwardly from the lower shell 11 and into the tubular support 20 are a plurality of air intake flues 23. At their lower ends the flues 23 are preferably coupled to the lower shell 11 by strainer caps 24 of approved construction to prevent the entrance of dust, insects or the like.

10 A bell shaped tubular member 25 having a supporting flange 26 is disposed upon the top member 16 of the outer shell and constitutes a continuation of the tubular member or air duct 18, the flare or curvature of the member 25 corresponding to and spaced from the flared end of the portion 22 of the member 21, as shown in Figs. 2 15 and 7.

15 Supported within the lower shell 11 is an annular gas burner 27 of approved construction, preferably supported by standards 28 from the bottom of the lower shell, and 20 provided with a plurality of orifices which form gas jets as shown.

25 The intake 29 for the lower burner is of the usual form, and leading into the intake is a feed pipe 30, the latter extending into 30 the upper shell or generator and upturned at the inner end as shown at 31.

30 The pipe 30 is supplied with a controlling valve 32, and operates to supply gas from the shell 15 to the burner 27.

35 Supported preferably by standards 33 above the end 16 of the upper shell or generator and surrounding the flaring portions 22 and 25, is a larger and upper annular burner 34.

40 A conventional intake 35 leads into the upper burner 34, and leading into the intake 35 is a feed pipe 36, the latter extending into the upper shell and terminating in an inwardly opening check valve 37 of approved 45 construction.

45 A pilot burner 38 of approved construction is connected through the top 16 of the upper shell and terminates in a discharge nozzle or tip 39.

50 The upper shell defined by the members 15, 16 and 17, as before stated, constitutes the generating chamber and is supplied with liquid hydro-carbon through feed pipe 40 and water through pipe 42, the pipes being provided with suitable thermostatic control devices represented conventionally at 43 and 44.

55 With an apparatus thus constructed the operation is as follows:

60 The liquid fuel is fed into the upper shell or generator through the feed pipe 41 under the control of the thermostat device 43, and the water through the feed pipe 42, the latter having a controlling valve 45. By this 65 means the "feed" to the upper shell or gener-

ator is effectually controlled and capable of being supplied at a predetermined rate, and when the commingled elements come in contact with the bottom 17 of the generator which is highly heated by the lower burner 70 27, they are volatilized and thus converted into a highly inflammable gas. A relatively small portion of this gas passes through the pipe 30 to the lower burner 27 and thereby supplies the latter, while the major portion 75 of the gas passes to the upper burner by the feed pipe 36, displacing the check valve 37 in its passage.

80 The gas generated in the upper chamber or generator thus passes to three localities in the apparatus, the lower burner, the pilot burner, and the main or upper burner.

85 The gas passes directly to the lower burner and the pilot burner, while the gas that passes to the upper burner is only the amount in excess of the requirements of the lower and the pilot burners, being held back by the check valve 37.

90 The thermostatic control of the liquid fuel and water is set at the minimum to insure the requisite burning of the lower and pilot burners, the check valve insuring the proper supply to the lower and pilot burners before any of the gas can reach the main burner.

95 The cool air enters through the intake flues 23 and passes thence through the space between the tubular members 18 and 21, and thence between the flaring portions 22 and 25, thus insuring the complete combustion of all of the gases by a constant supply of 100 highly heated fresh air directly over the flames of the main or upper burner 34.

105 The inner tube 21 likewise possesses the two fold function as a means in coaction with the tube 18 for conducting the heated air to the upper burner, but also as a conductor for any fumes which may rise from the lower burner.

110 The improved device is simple in construction can be inexpensively manufactured, and of any required size or capacity, and may be installed in any locality where highly heated air is required.

115 The preferred embodiment of the invention is disclosed in the drawings and set forth in the specification, but it will be understood that modifications within the scope of the claimed invention may be made in the construction without departing from the principle of the invention or sacrificing any 120 of its advantages.

125 Having thus described the invention, what is claimed as new is:—

1. In an apparatus of the class described, a generating chamber, a conductor for outside air formed of an outer and an inner flue extending through said generating chamber with their outlet ends flaring outwardly, a preliminary burner beneath said generating chamber in position to receive the air dis- 130

charged thereover from the flaring outlet of the air conductor flues, means for supplying hydro-carbon fuel to said generating chamber, means for supplying gas from said generating chamber to said preliminary burner, and means for supplying gas from said generating chamber to said main burner.

2. In an apparatus of the class described, a generating chamber, a tubular conductor for outside air extending through said generating chamber, a preliminary burner beneath said generating chamber, an annular main burner above said generating chamber and encompassing the discharge end of said tubular air conductor and adapted to receive the air uniformly from the same, means for supplying hydro-carbon fuel to said generating chamber, means for supplying gas from said generating chamber to said preliminary burner, and means for supplying

gas from said generating chamber to said main burner.

3. In an apparatus of the class described, a generating chamber, an air conductor extending through said generating chamber, a preliminary burner beneath the generating chamber, air intake flues leading to said air conductor flue and in position to receive the heat radiated from said preliminary burner, a main burner above said generating chamber, means for supplying hydro-carbon fuel to said generating chamber, means for supplying gas from said generating chamber to said preliminary burner, and means for supplying gas from said generating chamber to said main burner.

In testimony whereof, I affix my signature hereto.

GEORGE W. WOODS.
